UNITED STATES PATENT OFFICE.

JOHN DOWN AND JOSEPH A. RITTER, OF WALNUT CREEK, CALIFORNIA.

CLOSURE FOR RAILROAD CARS.

Application filed May 10, 1926. Serial No. 107,970.

The present invention relates to improvements in closures for railroad cars, and its particular object is to provide a closure adapted for cars in which loose grain is carried, the grain usually being loaded into the car from grain elevators and being discharged from the car by breaking away the door.

At the present time, it is customary to build up the closure step by step as the grain is loaded into the car by simply boarding up a door opening, while at the unloading of the car the boards are broken away so that the grain may roll freely through the door opening. A disadvantage of this procedure is that the nailing of the boards and the removal thereof takes considerable time, spoils the appearance of the door frame and results in enormous waste of material, due to the fact that the boards are hardly ever used over again.

It is the object of the present invention to provide a permanent door for grain cars of this character, the peculiar characteristics of the door being that it is suspended from a horizontal axis for free swinging motion in the door opening, that it is laterally expandable so that it may be interlocked with the door frame, and, furthermore, that it is slideable vertically and guided in such a manner that it may be pulled from its active position in the door frame to an inactive position in adjacent relation to the roof of the car, so as to be out of the way altogether.

Further objects and advantages of our invention will appear as the specification proceeds.

The preferred form of our invention is illustrated in the accompanying drawing in which Figure 1 shows a front view of our door in operative relation to the surrounding parts of a railroad car, Figure 2 a horizontal section taken along line 2-2 of Figure 1, Figure 3 a detail view of a locking means taken along line 3-3 of Figure 4, Figure 4 a plan view of the said locking means, Figure 5 a detail view of a driving connection for raising the door, Figure 6 a vertical section taken along line 6-6 of Figure 1, Figure 7 an enlarged detail view in side elevation of a carriage for the door and guide means therefor, Figure 8 an end elevation of the same mechanism, Figure 9 a fragmentary rear view of the bottom of the door, Figure 10 an enlarged detail view of an operating mechanism for expanding and contracting the door, Figure 11 a sectional view taken along line

11-11 of Figure 10 and Figures 12, 13, 14 and 15 various schematic views explaining the operation of our mechanism.

While we have shown only the preferred form of the invention, we wish to have it understood that various changes or modifications may be made within the scope of the claims hereto attached without departing from the spirit of the invention.

The door 1 is preferably made of a single plate of sheet metal and is of a width slightly less than that of the door opening 2 of the car 3. It is supported by means of a rod 4 secured to the back side of the door in parallel relation to the upper edge thereof, which rod is supported in two carriages 6, which latter comprise two grooved wheels 7 connected by links 8. These carriages, which are outside of the door opening, ride on bows 9 extending from a point below the top of the door as at 11 upwardly to run first substantially parallel to the wall of the car and later substantially parallel to the roof thereof, as is well illustrated in Figures 12 to 15. The lower end of each bow turns away from the wall of the car, as shown at 12, so as to be spaced therefrom and to allow the carriage 6 to be accommodated between the lower end of the bow and an opposing guide member 13 secured to the door frame.

It will be noted that this arrangement allows the door, when in its lowermost position, to swing back and forth freely in the door opening and to be moved upward when the carriage 6 is made to ascend the bow 9.

Such motion is imparted to the door by means of the chains 14 connecting the lower edge of the door, as at 16, with spools 17 on the horizontal shaft 18 mounted parallel and back of the upper frame member 19. Rotary motion may be imparted to this shaft by means of a second vertical shaft 21 mounted alongside of one of the vertical frame members 22 of the door opening through the bevelled gears 23 and 24. The shaft 21 extends through the bottom 26 of the car and is provided at the bottom with a wheel 27 having a handle 28 and a ratchet 29 adapted to be engaged by a pawl 31 for holding the same against reverse motion. The wheel is also formed with a series of annularly arranged perforations 32 adapted to receive the end of a hook 33 for locking the wheel against motion either way.

As stated before, the normal width of the door is such that the same freely swings in

the door opening. To allow the door to be interlocked with the door frame, we make the same laterally expansible in the following manner:—The bottom and top ends of 5 the door, which latter for the purposes of a grain car need only cover about two-thirds of the door opening, are turned over as at 36 and 37 to form grooves in which are arranged two wings 38 of substantially the same height 10 as the door and slidably so that the same may be projected on opposite sides beyond the width of the door for interlocking relation with the door frame, which latter is for this purpose formed with registering grooves 39. 15 The wings, which cover a substantial edge portion of the door, have rack bars 41 extending inwardly therefrom in parallel and spaced relation, the bars being guided by the plate 42 fastened to the door by means of bolts 43 20 and meshing with a pinion 44 fixed to a pin 46 extending through the door and the plate 42. The pin may be operated by means of a handle 47. The wings may be further guided for horizontal motion by means of two sets 25 of bolts 48 riding in slots 49. It will be seen that the wings may be projected outwardly by a turn of the handle 47 and may be drawn inwardly by a turn in the opposite direction. 30 The door is formed with a flap 51 at the bottom thereof, which latter is hinged to the door, as shown at 52, and is adapted to form a tight closure, so as to prevent the grain from rolling out underneath the door.

As seen from Figures 12 to 14, doors of this 35 character may be arranged on opposite sides of the car, provided the bows are arranged in such a manner as to allow the doors to clear one another when in an inactive position.

The door is operated in the following manner. 40 When it is desired to load the car, the door is swung into a vertical position within the frame opening, the handle 47 is operated to swing the wings outwardly into engagement with the grooves 39 and the wings 45 are locked in this position by means of a latch 50 pivoted to one of the wings at 51' and adapted to bear with its front end against the plate 42. The flap 51 at the bottom naturally assumes the position indicated in 50 Figure 6. The loading of the car through the opening above the door may now be proceeded with, the door remaining firmly locked until the place of destination has been reached. The grain, lying loosely in the 55 car, presses against the door from the inside. To unload the car, the latch 50 is removed and the handle 47 turned to draw the two wings inwardly. The width of the door being now less than that of the door opening, 60 the weight of the grain forces the door outwardly automatically, substantially into the position illustrated in Figure 13. The hinged flap 51, of course, does not place any obstacle in the way. A large portion of the 65 grain may flow out through the opening thus

furnished. The operator may then turn the wheel 27, after releasing the same from the hook 33, and thereby wind the chains 14 on the spools 17, whereby the bottom edge of the door is raised and the carriage 6 is caused to travel upward on the bows 9, going through the position indicated in Figure 14, and finally landing the door in the position shown in Figure 15; that is, in adjacent and parallel relation to the roof of the car. The entire 70 door opening is now clear, and the work of cleaning the car may be done unhampered. Where doors are provided on opposite sides, the same may be easily handled by means of two sets of properly shaped bows, as illustrated in Figures 12 to 15. The doors are locked in their respective positions by means of the hook 33, which, for this purpose, is introduced in one of the holes 32 of the 75 wheel 27.

To get the car ready for re-loading, the wheel 27 is released from the hook 33, and is turned to allow the doors to come down by their own weight. When the bottom of the door reaches the floor, the door is made to 80 register with the grooves 39, whereupon the handle 47 is turned for forcing the two wings into said grooves, whereby the door is interlocked with the frame. After applying the latch 50, the door is thus firmly held, and the 85 loading of the car may be proceeded with.

Having described our invention, we claim:

1. In combination with a box car having a door opening therein, a door of a width slightly less than the door opening, a rod secured to the inside face of the door in parallel relation and adjacent to the upper edge thereof, a carriage outside of the door opening on each end of the rod, said rod being pivotally supported in said carriages; an arched guide for each carriage, each guide being secured to the sides and to the top of the box car, a straight portion of each guide extending from a point below the top of the door upwardly substantially in parallelism with the side wall of the box car and spaced therefrom, so as to allow the traveling of the carriage between said side wall and the guide, a bent arched portion of the guide extending in continuation of the straight portion and substantially in parallelism with a roof of the box car, means to raise the lower edge of the door for forcing said carriages to ride on said guides and for simultaneously swinging said door outwardly around said pivot rod so as to permit the moving of the door by said raising means to a position between said guides and the top of the car, means for locking said raising means after the door is raised; and means for locking the door against swinging in the door opening when lowered.

2. In combination with a box car having a door opening therein, a door of a width slightly less than the door opening, a rod secured to the inside face of the door in parallel 130

relation and adjacent to the upper edge thereof, a carriage outside of the door opening on each end of the rod, said rod being pivotally supported in said carriages, an arched guide 5 for each carriage, each guide being secured to the sides and to the top of the box car, a straight portion of each guide extending from a point below the top of the door upwardly substantially in parallelism with the 10 side wall of the box car and spaced therefrom, so as to allow the traveling of the carriage between said side wall and the guide, a bent arched portion of the guide extending in continuation of the straight portion and substantially in parallelism with a roof of the 15 box car; flexible means connected to the lower

edge of the door for raising the door; rotatable means disposed adjacent to the upper edge of the door opening for winding said flexible means, thus forcing said carriages to 20 ride upon the guides and simultaneously swinging the door outwardly around said pivot rod; means for locking said winding means against rotation, and means laterally expandible beyond the side edge of the door 25 for locking the door against swinging in the door opening when lowered.

In testimony whereof we affix our signatures.

JOHN DOWN.

JOSEPH A. RITTER.
